UNITED STATES PATENT OFFICE

2,336,953

ROCK DRILL

Charles F. Osgood, Claremont, N. H., assignor to
 Sullivan Machinery Company, a corporation of
 Massachusetts

Application October 7, 1941, Serial No. 414,021

10 Claims. (Cl. 121—7)

This invention relates to rock drills and more particularly to improvements in a rotation release mechanism for a hammer rock drill.

An object of the present invention is to provide a novel rotation release mechanism. Another object is to provide an improved release mechanism for the rotation means of a hammer rock drill whereby steel rotation may be interrupted without interrupting operation of the drill hammer motor. Another object is to provide an improved rotation release mechanism having novel operating and controlling means. A further object is to provide an improved rotation release mechanism associated with the ratchet and pawl mechanism of the drill steel rotation means whereby the pawls may be released and held from engagement with the ratchet teeth thereby to interrupt drill steel rotation. A still further object is to provide a novel rotation release ring coaxial with the ratchet and pawl mechanism, which is rotatable into a position to release and hold the pawls from engagement with the ratchet teeth. Yet another object is to provide a novel means actuated by pressure fluid for rotating the release ring to effect pawl release, and having novel controlling means associated therewith. Still another object is to provide in a drill steel rotation means having a stationary pawl carrier and a rotatable ratchet ring, a rotatable release ring coaxial with the pawl carrier for releasing the pawls from engagement with the ratchet teeth thereby to release the ratchet ring for free rotation. A further object is to provide a rotation release mechanism which is simple and rugged in construction, and compact in design. With the above and other objects in view, this invention relates to certain novel features of construction, operation and arrangement of parts, an example of which is given in the specification and illustrated in the accompanying drawing, wherein:

Fig. 1 is a view in longitudinal vertical section through a rock drill in which an illustrative embodiment of the invention is incorporated.

Fig. 2 is an enlarged cross sectional view taken substantially on line 2—2 of Fig. 1.

Fig. 3 is an enlarged cross sectional view taken substantially on line 3—3 of Fig. 1.

Fig. 4 is a sectional view similar to Fig. 3 showing the release ring in rotation releasing position.

Fig. 5 is a perspective view of the release ring.

Fig. 6 is a detail sectional view taken on line 6—6 of Fig. 2.

In this illustrative embodiment of the invention, the improved rotation release mechanism is

associated with the drill steel rotation mechanism of a hammer rock drill. The rock drill is herein of conventional design and embodies a drill hammer motor comprising a motor cylinder 1 having a bore 2 containing a reciprocating hammer piston 3. The hammer piston has a forwardly projecting striking bar 4 for delivering impact blows to the shank of a conventional drill steel 5 carried within a usual rock drill chuck 6. The hammer motor cylinder has a front head 7 and a rear head 8 and arranged at the rear end of the motor cylinder is a rear head block 9. The rear head block carries a throttle valve mechanism 10 for controlling the flow of pressure fluid from a suitable source of supply through passage means 11 to a fluid distributing valve mechanism 12.

As is usual in rock drills of the type disclosed, a rotation mechanism operated by the hammer piston is provided for rotating the drill steel as the latter is percussively actuated. This rotation mechanism includes a spirally grooved rifle bar 13 slidably interlocked with a rifle nut 14 secured within the hammer piston. Associated with the rifle bar is an intermittent grip mechanism for intermittently holding the rifle bar against rotation in one direction whereby rotary motion is imparted to the hammer piston, preferably during the return stroke of the latter. The rotary motion of the hammer piston is transmitted to the drill steel in the usual manner through straight grooves 15 on the piston striking bar 4 slidably interlocked with a chuck nut 16 secured to a rotatable chuck sleeve 17 of the chuck 6. The intermittent grip mechanism includes a rotatable grip or ratchet ring 18 having internal ratchet teeth 19 and integrally secured to the rifle bar 13. Arranged concentrically within the rotatable ratchet ring is a stationary pawl carrier 20 which carries usual spring-pressed gripping elements or pawls 21 engaging the teeth of the ratchet ring. The pawl carrier 20 has its hub 22 keyed at 23 to a stationary cylindric projection 24 integral with the rear head block 9. The rifle bar 13 has a rearward cylindric portion 25 journaled in a bearing sleeve supported within the stationary pawl carrier. As shown in Fig. 2, the throttle valve mechanism 10 includes a throttle valve 26 received in a transverse bore in the rear head block 9 and having an operating handle 27. A supply hose connection 28 is adapted to supply pressure fluid through a space 29 to the hollow interior of the throttle valve and the latter is adjustable to control the flow of pres-

sure fluid to the fluid distributing valve mechanism in a well known manner.

Now referring to the improved rotation release mechanism, it will be noted that arranged in a bore 30 between the rear surface of the ratchet or grip ring 18 and the rear head block is a rotatable release annulus or ring 31, and this annulus or ring is cut away or notched at 32 at four points spaced equally about its inner periphery. The release ring is guided for rotary movement but is held against endwise movement in a suitable manner. In this instance, the pawls 21 are elongated and project outwardly at 33 within the release ring 31, and the cut-away portions or notches 32 on the release ring permit the pawls 21 to move into engagement with the ratchet teeth 19 in a manner shown in Fig. 3. When the release ring is rotated from the position in Fig. 3 to that shown in Fig. 4, the release ring at its inner periphery engages the pawls 21 to move the latter from engagement with the ratchet teeth and to hold the pawls in released position. The operating means for the release ring comprises a fluid actuated plunger 34 having an annular groove 35 in which a lug or pin 36 secured to the release ring projects as shown in Fig. 6. The plunger 34 has at one end a piston 37 received in a bore 38 and at its other end a projection 39 engageable with a plug 40 for limiting movement of the plunger. Arranged between the plunger and the plug 40 and encircling the projection 39 is a coil spring 41 which constantly urges the plunger in one direction. Arranged in a plug 42 secured to the rear head block 9 is a plunger valve 43 reciprocably mounted in a bore 44. The stem 45 of this plunger valve has a push button 46, and a coil spring 47 urges the plunger valve toward its rearmost position. The valve receiving bore 44 is connected by a passage 48 to the pressure fluid space 29 of the throttle valve mechanism 10 so that the passage 48 is in constant communication with the source of pressure fluid supply. A passage 49 connects the valve receiving bore 44 with the bore 38 containing the plunger-piston 37. A branch passage 50 connects the passage 49 with a vent passage 51. The piston valve 43 has spaced annular grooves 52, 53, and when the valve is in the position shown in Fig. 1, the passage 49 communicating with the piston receiving bore 38 is in communication with the vent passage 51 through the valve groove 52.

The mode of operation of the improved rotation release mechanism is as follows: When the piston valve is moved forwardly from the position shown in Fig. 1, the valve groove 53 connects the supply passage 48 with the passage 49 so that pressure fluid may flow to the bore 38 to act on the piston 37. The pressure fluid acting on the plunger-piston 37 moves the plunger 34 axially against pressure of the coil spring 41, and through the groove 35 and pin 36 the release ring 31 is rotated into a position to disengage the pawls from the ratchet teeth thereby to release the ratchet ring for free rotation. When the ratchet ring is free to rotate, rotation of the drill steel 5 is interrupted and the hammer piston may reciprocate percussively to actuate the drill steel while steel rotation is discontinued and at this time the rifle bar 43 freely oscillates back and forth as the hammer piston reciprocates. When it is again desired to effect drill steel rotation, the push button 46 is released to permit the piston valve 43 to be moved rearwardly by the coil spring 47 into the position shown in Fig. 1, and

at that time the fluid supply to the passage 49 is cut off and the passage 49 is connected to atmosphere through the branch passage 50, valve groove 52 and the vent passage 51. When the pressure fluid in the bore 38 is vented to atmosphere, the coil spring 41 moves the plunger 34 axially in the opposite direction thereby to effect rotation of the release ring 31 back to its initial inoperative position shown in Fig. 3. When the release ring 31 is released and has assumed the position shown in Fig. 3, the cut-away portions or notches 32 permit engagement of the pawls 21 with the ratchet teeth.

As a result of this invention, an improved drill steel rotation mechanism for a rock drill is provided whereby the drill operator may interrupt drill steel rotation at will in an improved manner. It will further be evident that by the provision of the improved rotary release ring associated with the ratchet and pawl mechanism and arranged in the manner described, the pawls may be released from engagement with the ratchet ring in an improved manner. It will further be evident that the improved structure is comparatively simple and rugged, is relatively compact and may be readily and easily operated. Other uses and advantages of the invention will be clearly apparent to those skilled in the art.

While there is in this application specifically described one form which the invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. In a rock drill, rotation mechanism adapted to effect rotation of a drill steel comprising an intermittent grip mechanism, said grip mechanism including a carrier element, gripping means carried by said element and a grip ring element with which said gripping means is engageable, said carrier and grip ring elements being relatively rotatable, a rifle bar connected to one of said relatively rotatable elements, a rotary release ring arranged at one end of said carrier element and engageable with said gripping means to effect upon rotation thereof release of said gripping means from said grip ring element, and means for effecting rotation of said release ring relatively to said grip mechanism.

2. In a rock drill, rotation mechanism adapted to effect rotation of a drill steel comprising an intermittent grip mechanism, said grip mechanism including a carrier element, gripping means carried by said element and a grip ring element with which said gripping means is engageable, said carrier and grip ring elements being relatively rotatable, and said gripping means having a portion projecting outwardly beyond one end of said carrier and ring elements, a rifle bar connected to one of said relatively rotatable elements, a rotary release ring arranged at one end of said carrier element and engageable with the projecting portion of said gripping means to effect upon rotation thereof release of said gripping means from said grip ring element, and means for effecting rotation of said release ring relatively to said grip mechanism.

3. In a rock drill, rotation mechanism adapted to effect rotation of a drill steel comprising an intermittent grip mechanism, said grip mechanism including a stationary carrier, gripping means

carried by said carrier and a rotatable grip ring with which said gripping means is engageable, a rifle bar connected to said rotatable grip ring, a rotary release ring arranged in adjacency to said carrier and engageable with said gripping means to effect upon rotation thereof release of said gripping means from engagement with said grip ring, and means for effecting rotation of said release ring relatively to said grip mechanism.

4. In a rock drill, rotation mechanism adapted to effect rotation of a drill steel comprising intermittent grip mechanism, said grip mechanism including a stationary carrier, gripping means carried by said carrier and a rotatable grip ring with which said gripping means is engageable, said gripping means having a portion projecting outwardly beyond one end of said carrier and grip ring, a rotary release ring arranged at one end of said carrier and engageable with the projecting portion of said gripping means to effect upon rotation thereof release of said gripping means from engagement with said grip ring, and means for effecting rotation of said release ring relatively to said grip mechanism.

5. In a rock drill, rotation mechanism adapted to effect rotation of a drill steel comprising intermittent grip mechanism, said grip mechanism including a stationary carrier, gripping means carried by said carrier and a rotatable grip ring with which said gripping means is engageable, a rifle bar connected to said rotatable grip ring, a rotary release ring arranged in adjacency to said carrier and engageable with said gripping means to effect upon rotation thereof release of said gripping means from engagement with said grip ring, means for effecting rotation of said release ring relatively to said grip mechanism, said release ring having a notch at its inner periphery for permitting movement of said gripping means into engagement with said grip ring when said release ring is in operative position.

6. In a rock drill, rotation mechanism adapted to effect rotation of a drill steel comprising intermittent grip mechanism, said grip mechanism including a stationary carrier, gripping means carried by said carrier and a rotatable grip ring with which said gripping means is engageable, said gripping means having a portion projecting outwardly beyond one end of said carrier and grip ring, a rotary release ring arranged at one end of said carrier and engageable with the projecting portion of said gripping means to effect upon rotation thereof release of said gripping means from engagement with said grip ring, means for effecting rotation of said release ring relatively to said grip mechanism, said release ring having a notch at its inner periphery within which said projecting portion is received for

permitting movement of said gripping means into engagement with said grip ring when said release ring is in inoperative position.

7. In a rock drill, drill steel rotation mechanism including intermittent grip mechanism, said grip mechanism having gripping means, and means for interrupting operation of said grip mechanism including a rotatable release ring arranged in coaxial relation with said grip mechanism and rotatable into engagement with said gripping means to render the latter inoperative, and means for effecting rotation of said release ring relative to said grip mechanism.

8. In a rock drill, drill steel rotation mechanism including intermittent grip mechanism, said grip mechanism having gripping means, and means for interrupting operation of said grip mechanism including a rotatable release ring arranged in coaxial relation with said grip mechanism and rotatable into engagement with said gripping means to render the latter inoperative, and means for effecting rotation of said release ring relative to said grip mechanism, said rotation effecting means including a fluid actuated plunger engageable with said release ring.

9. In a rock drill, drill steel rotation mechanism including intermittent grip mechanism, said grip mechanism having gripping means, and means for interrupting operation of said grip mechanism including a rotatable release ring arranged in coaxial relation with said grip mechanism and rotatable into engagement with said gripping means to render the latter inoperative, and means for effecting rotation of said release ring relative to said grip mechanism, said rotation effecting means including a fluid actuated plunger engageable with said release ring, said plunger having an annular peripheral groove and said release ring having an operating pin projecting within said groove.

10. In a rock drill, rotation means for a drill steel comprising ratchet and pawl mechanism, said ratchet and pawl mechanism including relatively rotatable pawl carrier and ratchet elements, said carrier element carrying pawls movable into and out of engagement with said ratchet element, and means for interrupting drill steel rotation at the will of the operator including rotary release means coaxial with said ratchet and pawl mechanism and engageable with the pawls for moving the same upon rotation of said release means out of engagement with the ratchet element, and means for effecting rotation of said release means relative to said ratchet and pawl mechanism, said release means including a rotary release ring and said rotation effecting means including a plunger for rotating said release ring.

CHARLES F. OSGOOD.
